UNITED STATES PATENT OFFICE

99,393

DESIGN FOR AN APARTMENT FROCK

Harry H. Hommon, Decatur, Ill., assignor to Home Manufacturing Company, Decatur, Ill.

Application March 20, 1936, Serial No. 61,702

Term of patent 7 years

To all whom it may concern:

Be it known that I, Harry H. Hommon, a citizen of the United States, and a resident of Decatur, in the county of Macon and State of Illinois, have invented a new, original, and ornamental Design for an Apartment Frock, of which the following is a specification, reference being had to the accompanying drawing, forming a part of this specification.

Fig. 1 is a front view of a frock showing my design;

Fig. 2 is a rear view of the frock shown in Fig. 1.

I claim:

The ornamental design for an apartment frock, substantially as shown.

HARRY H. HOMMON.
